Primary Examiner — Patricia A Palasik(74) *Attorney, Agent, or Firm* — STETINA GARRED BRUCKER & NEWBOLES**CLAIM**

The ornamental design for a welding torch as shown and described.

DESCRIPTION

FIG. 1 is a front elevation view of a welding torch showing my new design;

FIG. 2 is a back elevation view thereof;

FIG. 3 is a top plan view thereof;

FIG. 4 is a bottom plan view thereof;

FIG. 5 is a right elevation view thereof;

FIG. 6 is a left elevation view thereof;

FIG. 7 is an enlarged right, front, top perspective detail view of the top portion of the welding torch;

FIG. 8 is an enlarged left, back, bottom perspective detail view of the top portion of the welding torch;

FIG. 9 is an enlarged right side detail view of the top portion of the welding torch;

FIG. 10 is an enlarged left side detail view of the top portion of the welding torch;

FIG. 11 is an enlarged detail view of the nozzle tip shown removed for clarity;

FIG. 12 is a center horizontal cross-sectional view taken along line 12 of the nozzle tip shown in FIG. 11 shown removed for clarity; and,

FIG. 13 is an exploded view of the welding torch in FIG. 11.
